UNITED STATES PATENT OFFICE

EDWARD HOUGHTON, OF NIAGARA FALLS, NEW YORK

FEEDING MECHANISM FOR SHEET MATERIAL

Application filed March 26, 1928. Serial No. 264,816.

The present invention relates to feeding mechanisms for sheet material. An object of the invention is to provide a novel construction which will permit the delivery by gravity of sheets of material one at a time from the bottom of a stack.

To this and other ends, the invention consists of certain parts and combinations of parts all of which will be hereinafter described: the novel features being pointed out in the appended claims.

In the drawings:

Fig. 1 is a view in elevation of the cabinet with the front wall removed showing the feeding mechanism enclosed;

Fig. 2 is a vertical section through the cabinet, showing the feeding mechanism in side elevation;

Fig. 3 is a section on the line 3—3, Fig. 2;

Fig. 4 is a section on the line 4—4, Fig. 5;

Fig. 5 is a section on the line 5—5, Fig. 2 looking in a downward direction;

Fig. 6 is a section on the line 5—5, Fig. 2 looking upwardly at the stack holding means;

Fig. 7 is an enlarged fragmentary view of the stack holding means; and

Fig. 8 is a fragmentary section on the line 8—8, Fig. 6.

The invention, in this instance, is illustrated in a vending machine which will deliver cards arranged within a cabinet to a point outside of the cabinet. In this embodiment, 1 indicates the rear wall of the cabinet, 2 the front wall and 3 the side walls. The cabinet has an interior compartment 4 which encloses the stack holding means.

The stack holding means, in this instance, comprises four uprights 5 of substantially W shape in cross section, these uprights being so arranged that elongated rectangular shaped cards 6 when arranged to cross one another alternately in the stack will be guided at their projected ends by the uprights to descend readily in the stack holding means.

The uprights are bolted at 6^a to a base member 7 having an opening 8 of cross formation. This base plate is supported over an opening 9 in the bottom wall of the chamber 4 and projects downwardly in said opening so that the cards or sheet pieces may drop from the

stack holding means through the opening onto a chute 10 to be delivered by the latter to the exterior of the casing by way of an opening 11 in the front wall of the casing.

With the end in view of retaining the stack in the stack holding means, and, at the same time, permitting the feeding of the sheets from the bottom of the stack, one at a time, there is provided two means which alternately acts as feeders and retainers. Each of these means, in this instance, embodies two members 12, pivoted at 13 to the base member 7 and simultaneously controlled to engage the next lowest sheet piece in the stack to hold the stack against dropping through the opening 8 while the other of said means is being operated to release the lowest card in the stack so that the two means operate alternately to engage the next lowest card in the stack and hold said stack through said card while the lowest card is released by the other means.

The alternate operation of the two feeding and retaining means may be effected in any suitable manner. In this instance, a motor 14 drives a shaft 15 on which are arranged two disk cams 16 and 17. Mounted to rock on opposite sides of the shaft 15 are two rock shafts 18 and 19. These rock shafts have respectively arms 20 and 21 provided with lateral projections, 22 and 23 engaging the cam disks 16 and 17 respectively. The shafts 18 and 19 also have arms 24 and 25 respectively which are pivotally connected to vertical slides 26 and 27. On these slides 26 and 27 are cross arms 28 and 29 respectively. The cross arm 28 has two links 30 pivoted thereto while the cross arms 29 has two links 31 pivoted thereto. The links 30 pivotally connect to crank arms 32 on the shafts of two of the pivoted retainers 12 arranged on opposite sides of the stack, while the links 31 connect with crank arms 33 on the shaft of the other two retainers 12 situated on two other opposite sides of the stack holding means.

In order to insure the descent of the sheet pieces in the stack holding means, a weighted follower 34 of cross formation may be employed. This follower may also be employed as part of an indicating means for indicating

substantially the number of sheet pieces in the stack from the exterior of the chamber 4, the chamber 4 having an opening 35 in its top wall through which an indicator slide 36 5 may operated. This slide is guided on a guideway 37 within the chamber 4 and is connected to the follower 34 by a flexible cable 38 secured at 39 to the follower, extending upwardly through the top of the stack holding means over a pulley 40 thence to a pulley 41, the pulleys 40 and 41 being supported on the top wall of the chamber 4. From the pulley 41 the cable 38 passes about a pulley 42 on the indicating slide 36 and has its end 10 anchored at 43 to the top wall of the chamber 4 on that side of the slide 36 opposite the side on which the pulley 41 is arranged. As the follower 34 drops with the lowering of the stack, the slide is elevated and the indications 44 thereon giving approximately the 15 number of cards or sheet pieces remaining in the stack.

The operation of the invention will be understood from the foregoing but it may be 20 summarized as follows. The stack holding means is filled or substantially filled with cards or sheets in cross relation, as illustrated in the drawings and the lowermost card is held by two of the retainers 12, as illustrated in Fig. 8. The motor 14 being started, first moves the other pair of retainers 12 into engagement with the next lowest card in the stack, and, thereafter, those retainers that hold the lowest card in the stack, move from 25 retaining position to drop such card by gravity onto the chute 12. The motor is controlled in any suitable manner but preferably so that it automatically stops when two of the retainers are in engagement with the lowermost 30 card in the pack and the other two retainers are away from retaining position. The motor 14 can be continuously operated so that the sheet devices will drop one at a time from the stack when the feeding means is used in 35 other relations.

What I claim as my invention and desire to secure by Letters Patent is:

1. In a sheet feeding mechanism the combination with a stack holding means having a bottom discharge, of two retaining means for sustaining the stack of sheets in said stack holding means, and means for operating said two means alternately to cause one of said two means to engage the next lowest sheet in the stack and the other to release the lowest sheet in the stack.

2. In a sheet feeding mechanism the combination with a stack holding means having a bottom discharge, of two retaining means for sustaining the stack of sheets in said stack holding means, each of said means comprising two retainers and means connecting said two retainers to move said retainers simultaneously toward and from retaining position, and means for operating said two retaining

means alternately to cause the retainers of one to engage the next lowest sheet in the stack and the retainers of the other to reach the lowest sheet in the stack.

3. In a sheet feeding mechanism the combination with a stack holding means having a bottom discharge, of two retaining means for sustaining the stack of sheets in said holding stack means, each of said retaining means comprising two pivoted retainers; and means for moving the retainers comprising two slides, two links pivoted to each slide and to two of the retainers at points eccentric to the pivots of said retainers, and means for operating said slides alternately to cause two of the retainers to engage the next lowest sheet in the stack and the other two retainers to release the lowest sheet in the stack.

4. In a sheet feeding mechanism the combination with a stack holding means having a bottom discharge, of two retaining means for sustaining the stack of sheets in said stack holding means, each of said retaining means comprising two movable retainers, and means for moving said two retaining means comprising two slides each connected to two of the retainers, two rock shafts each having two arms, one of said arms being connected to one of the slides, an operating shaft, and two cams on the operating shaft cooperating with the other arms on the rock shafts, one for each rock shaft.

5. A sheet feeding mechanism comprising a stack forming means having a bottom discharge, means for feeding the sheets one at a time through the discharge, an enclosing casing for the stack forming means, a movable indicator viewable from the exterior of the enclosing casing, a follower in the stack forming means, and a connection between the follower and the indicator for moving the indicator upwardly as the follower descends in the stack forming means.

6. In combination with a stack of elongated articles arranged one upon another in crossed relation, of two mechanisms successively operating to engage the next lowest article in the stack beyond opposite sides of the lowest article to support the stack while the outer of said mechanisms moves to release the lowest article from the stack by gravity.

EDWARD HOUGHTON.
